PACKAGING

J. Showles MacLean, Toledo, Ohio, assignor to
The Franklin Creamery Company, Toledo,
Ohio, a corporation of Ohio

Application July 24, 1936, Serial No. 92,493

6 Claims. (Cl. 206—56)

This invention relates to packaging.

This invention has utility when incorporated in single service sanitary packages for edibles not only for initially completely encasing of the package charge but also for progressive dispensing thereof as consumed.

Referring to the drawing:

Fig. 1 is a side elevation of a length of printed tubing, the preparation of which is a step toward production of packages hereunder;

Fig. 2 is a view similar to Fig. 1, in which the tubing has been encased with a wrapper or sleeve;

Fig. 3 is a section longitudinally through a completed empty package of the invention herein as supplied to the packer for storage prior to charging;

Fig. 4 is a plan view of the device of Fig. 3;

Fig. 5 is a section longitudinally through a charged package having the outer wrapper shifted to position ready for folding to form a closure for the end through which the package was charged;

Fig. 6 is a side elevation of a completed filled package; and

Fig. 7 is a plan view of Fig. 6.

The initial step in the manufacture of packages hereunder is the production of a continuous tube 1 of heavy paper, cardboard, or like relatively rigid material, and the placing thereon of a series of indicia 2 by printing or other marking means. Wrapper 3 is then placed about the tube 1 and may be preferably of a transparent or translucent, readily foldable flexible stock. In placing the wrapper 3 about the tube 1 it is desirable to have a coaxial fit therebetween preventing self shifting or relative disturbance between the tubes one to the other but permitting ready manual shifting of the wrapper 3 along the tube 1.

The double-walled continuous tube is then cut into predetermined lengths 4, the length of the element and the marking 2 having been so calculated that each bears a complete marking in a like position.

The element 4 is then provided with embossed rib 5 adjacent one end thereof, the rib being about the element 4 and bulging outwardly to provide seat or groove 6 on the interior thereof for fixedly positioning disc 7 as a frictionally anchored closure for one end of the tube, thereby held against ready snapping out or displacement.

Rod or stem 8 may extend through opening 9 centrally of the disc 7 to have disc or diaphragm 10 fixed on the end thereof within the element 4, the disc 10 being shiftable by the rod 8 along the interior of the element 4 to and from delivery end 11 as remote from the end 12 sealed by the disc 7.

The rod 8 may have terminal portion 13 extend outwardly from the disc 7 as a means to be manually gripped for operating the disc or piston 10. By moving the piston 10 to adjacent the end 11, a small compact cylindrical device is formed permitting ready storage and shipping while simultaneously maintaining the interior 14 of the element 4 free from contamination.

At the place where the package is to be charged, an operator may grip the rod terminus 13 and pull the piston 10 against the disc 7. The charge 15 may then be placed in the chamber 14, with no soiling nor smearing of the exterior of the tube 1 or the indicia 2. The sleeve or wrapper 3 may then be shifted toward the delivery end 11 to provide extension 16 therebeyond which may be readily twisted and folded into a closure 17 therefor. The package is then complete and ready for the customer. The material therein is completely sealed against contamination until ready for use. It may be handled upright or on its side with no hazard of spilling its semi-fluid contents such as ices or ice cream. The package herein being primarily designed for frozen confections, the operator handling the same usually has damp hands and this permits ready gripping of the wrapper 3 to slide it along the inner tube.

The rib 5 insures a maintenance of the wrapper 3 in proper position until use, the initial shifting of the wrapper being resisted thereby.

By twisting the extension 16 into the closure 17, there is provided tip 18 as a handle-like knob facilitating opening of the dispensing end. In opening, the tip 18 may be grasped and the shield pulled off the tube 1, following which the contents may be delivered through the open end 11 as desired by operation of the rod 8.

The piston 10 is anchored with the stem 8 by eyelet 19.

The container has its delivery end maintained sanitary and against contamination by the sleeve 3. In shifting the wrapper 3, the indicia is exposed and increases readability, while complete removal of the wrapper fully exposes any portion thereof which might extend thereunder while providing a seal. The materials from which the package is formed being preferably of paper stock, provide desirable insulating qualities against heat from the hand of the consumer being transferred to a frozen confection.

What is claimed and it is desired to secure by United States Letters Patent is:

1. A package comprising a tubular container having a delivery end, a terminal closure for the opposite end, and a wrapper assembled to con-

form exteriorly with the container between said ends, said wrapper being shiftable relatively to the container to provide an integral extension of said wrapper beyond the delivery end, said wrapper integral extension being there foldable to provide a closure for the delivery end of the container.

2. A dispensing package comprising a tube having a delivery end and an endless seat adjacent the opposite end, a closure disc fixed by said seat, a rod through said closure, a diaphragm movable by said rod for shifting container-charged material through the delivery end, a wrapper mounted and conforming exteriorly to the tube and so constructed to be shiftable relatively along the tube to provide an integral extension beyond the delivery end foldable into a closure therefor, said tube so constructed to mount the wrapper and house the rod to be thereby adapted to be telescoped within the tube in unfilled condition of the package for compact displacement.

3. A package comprising a tube, there being a rib outwardly and about the tube adjacent one end thereof providing a groove on the inner side thereof, a wrapper about the tube extending inwardly past the rib to be thereby held against relative shifting between the wrapper and tube, and a tube terminal closure mounted in said groove, said rib providing resisting means against

initial shifting of said wrapper to hold the wrapper to conform to the tube exterior.

4. The method of packaging material in a double-walled container comprising closing one end of said container, charging said container through the open end with the material to be packaged, shifting the outer wall of the container longitudinally of the inner wall to provide an integral extension beyond the open end and folding said integral extension into a closure therefor.

5. A package comprising a tube having an endless seat adjacent an end thereof, a closure disc for an end of the tube engaged in said seat, and a wrapper conforming to the tube exterior throughout the length of said tube and wrapper, said wrapper being shiftable relatively to the tube to provide an integral extension remote from the disc, said extension being collapsible to provide a closure for the package.

6. A container having concentric inner and outer walls, an end in the container having a seat bulging said walls for the inner wall to interfit with the end and for the inner wall to interfit with the outer wall, said outer wall being shiftable as to said bulging to form an integral extension from an end wall collapsible to form a closure opposite to said end.

J. SHOWLES MACLEAN.
